EUGENE HEINRI TARTRAIS
INVENTOR:
Otto H. Hunk
BY HIS ATTORNEY.

UNITED STATES PATENT OFFICE.

EUGÈNE HENRI TAETRAIS, OF MAISONS-LAFFITTE, FRANCE.

FUEL-SUPPLY MEANS FOR HEAVY-OIL ENGINES.

Application filed March 7, 1924, Serial No. 697,515, and in France March 14, 1923.

My invention has for its object an arrangement for preventing the formation of gas bubbles within the liquid fuel which is supplied to heavy oil engines by injection pumps. The gas bubbles are formed within the liquid fuel itself when the latter comes into contact with the hot or even the warm parts of the engine, and they consist of volatile hydrocarbon gas. This effect is chiefly observed in the case of certain fuels whose fluidity is insufficient and which must be preheated.

The apparatus according to the invention comprises a receptacle which is so disposed as to be heated for instance by the cooling water of the engine, and which forms part of a circuit comprising the main fuel tank and a circulating pump, the said receptacle being provided at its upper part with an outlet valve urged upon its seat by a calibrated spring, the feed pipe of the injection pump opening laterally into the said receptacle. Any gases which may be contained in the liquid fuel are discharged within the receptacle by the action of heat, and will return together with the excess of liquid to the main fuel tank, while the fuel delivered to the injection pump is entirely freed from gas. Other features and advantages of the invention will be disclosed in the following description:

The appended drawing shows by way of example an embodiment of the invention as applied to the engine of a motor vehicle.

Fig. 1 is a front view of the engine.

Fig. 2 is a vertical section of the preheating box.

1 is the main fuel tank, which is disposed at the rear of the vehicle. The pipe 2 extending from the bottom of the said tank constitutes the suction pipe of the circulating pump 3 which is driven by the engine 4 and may be of the gearing or the paddle type. 5 is the discharge pipe of the said pump; the fuel issuing through said pipe flows through the central chamber 6' of the preheating box 6, (Fig. 2). The fuel passes through a removable filter 7 and is discharged along with the gas through the valve 8 urged upon its seat by the spring 9, and returns thence through the pipe 14 to the top of the tank 1.

The chamber 6' is surrounded by a hot water jacket 10 provided with the pipes 17, 18 and in which the cooling water of the engine is caused to circulate. 15 is the ra-

diator of the engine, 16 the water pump and 19 the radiator return tube. The suction pipe 13 of the injection pump 12 is connected with the conduit 11 situated at one side of the said preheating box. 20 and 21, (Fig. 1) are the discharge pipes of the said injection pump.

During the operation, the liquid fuel is forced through the said preheating box by the pump 3, while at the same time the injection pump withdraws from the said box a certain amount of fuel through the conduit 11 and delivers it to the engine through the tubes 20 and 21. By reason of the heat prevailing in the said box, all gases contained in the liquid fuel will be discharged and due to the position of the pipes 11, the gas bubbles will escape preferably through the valve 8 located at the upper part of said box, and will thus return through the pipe 14 to the main fuel tank 1 together with the excess of liquid fuel. The combustible which is supplied to the injection pump will thus be freed from all gas bubbles in a very effective manner, and it is also filtered by the filter 7 contained in the said box.

It will be observed that by the use of the discharge valve 8 provided with a calibrated spring, a determined pressure will prevail in the chamber 6' due to the pressure of said spring. This pressure, which has preferably a small value, for instance two or three atmospheres, appears to prevent any further formation of bubbles, or at least reduces the volume of the same to a great extent; at all events, the operating conditions are found to be much improved. This effect also facilitates the supply of liquid to the pump and thus increases the output of the latter.

In the particular case of a motor vehicle in which the main fuel tank is situated at the rear and at a low level, the auxiliary pump 3 withdraws fuel directly from the tank, as observed, and this will dispense with the use of fuel elevating or suction devices, or the use of gas or air pressure upon the fuel.

Obviously, my said invention is not limited to the constructional forms herein represented, which are given solely by way of example.

Having now described my invention what I claim as new and desire to secure by Letters Patent is:

1. In combination with the fuel pump of a liquid fuel internal combustion engine, a

- heated receptacle through which the fuel is caused to flow from bottom to top and according to a substantially straight path, the inlet pipe of said pump opening laterally in 5 to said receptacle and at the upper part thereof, and means for returning the surplus of fuel and the bubbles which are formed within said liquid fuel from the top of said receptacle to the fuel feed tank.
- 10 2. A fuel feeding system for a liquid fuel internal combustion engine, comprising a fuel feed tank, a main fuel pump, a heated receptacle at the upper part of which the inlet pipe of said fuel pump opens laterally, an auxiliary pump pumping out of said tank and forcing the fuel through said receptacle from bottom to top and according to a substantially straight path, a return pipe connecting the top of said receptacle to said tank, an adjustable discharge valve on 20 said return pipe whereby the bubbles which are formed within the liquid fuel are discharged, and means for heating said receptacle.

In testimony whereof I have signed my 25 name to this specification.

EUGÈNE HENRI TARTRAIS.
